IRONING MACHINE

Application filed October 12, 1929. Serial No. 399,296.

This invention relates to ironing machines having a rotative power-driven ironing roll or cylinder and a heated ironing shoe or iron, and having means for operating the ironing shoe and means for operatively connecting the ironing roll with the driving mechanism and for disconnecting the same.

The principal object of the invention is to provide an improved, simple, economical and efficient ironing machine.

Further objects of the invention are to provide an ironing machine having improved means for operating the ironing shoe comprising means for moving the shoe toward and from the ironing roll, means for holding the shoe in yielding operative relation to the roll and material to be operated upon, and means for releasing and permitting the movement of the ironing shoe away from the roll with facility and in an efficient manner; to provide improved, simple and efficient means associated with and adapted to be operated concurrently with the operation of the shoe-operating means, for operatively connecting the ironing roll with the driving mechanism and for disconnecting the same to effect the rotation and stopping of the roll in the desired relation to the movements of the ironing shoe toward and from the same; to provide improved manually-operable means for operating the ironing shoe and for starting and stopping the rotation of the roll including means for locking and releasing the shoe-operating means and shoe and means for closing and releasing the clutch for connecting the ironing roll with the driving mechanism and disconnecting the same, all adapted to be operated with ease and facility through the medium of a single hand lever having the simplest possible mode of operation and requiring the application of the minimum amount of power by the operator relatively to the desired results and advantages accomplished.

Other and further objects of the invention will appear from the following description and claims, and from an inspection of the accompanying drawings which are made a part hereof.

The invention consists in the features, com-

bination, details of construction and arrangement of parts herein described and claimed.

In the accompanying drawings—

Figure 1 is a front view in elevation of an improved ironing machine constructed in accordance with our invention, with part of the lower enclosing casing and parts of the ironing roll and table broken away and omitted;

Fig. 2 is an enlarged end view in central vertical section of the machine shown in Fig. 1, showing the upper part of the casing in section and showing the mechanism located in said casing in elevation, with the shoe-operating mechanism in position to hold the ironing shoe in operative relation to the roll and the clutch-operating mechanism in position to operatively connect the ironing roll with the driving mechanism for rotating the roll;

Fig. 3 is a similar view showing the mechanism shown in Fig. 2 in the position which it should occupy when the ironing shoe is released and out of engagement with the ironing roll and the clutch is released and the ironing roll disconnected from the driving mechanism;

Fig. 4 is a front view in vertical section of the mechanism shown in Fig. 2;

Fig. 5 is a plan view of the mechanism shown in Figs. 2, 3 and 4, with the upper part of the casing broken away; and

Fig. 6 is a perspective view showing the details of the clutch construction.

In constructing an improved ironing machine in accordance with our invention, we provide a machine frame 1 having a base 2 on which is supported a hollow upright pedestal or frame 3 which, by preference, comprises a lower enclosed casing or frame portion 4 and an upper hollow enclosed casing or frame portion 5 which is supported on and secured in rigid relation to the lower frame portion 4 by suitable securing means. For example, an angular metallic frame member 6, having an upright inner depending flange 7 and a horizontally outwardly projecting marginal flange 8, is rigidly secured to the top margin of the lower frame portion or casing 4; and the upper frame or casing portion 100

5 is provided with an inwardly extending horizontal bottom flange which overlaps and is firmly secured to the angular frame member 6 by threaded securing screws or bolts which extend through and in threaded engagement with suitable threaded openings in the flange 9 and through suitable openings in the horizontal flange 8, or other suitable securing means.

10 A work table 11, formed, by preference, of sheet metal and having a curved upwardly projecting rear marginal portion 12 and a straight front margin 13, is interposed and firmly secured between the adjacent flanged margins of said frame or casing portions 4 and 5.

15 A rotative horizontal ironing roll or cylinder 14 is provided which comprises, by preference, a metallic cylindrical peripheral wall 15, the opposite ends of which are fixed to concentric cylindrical heads 16 journaled on a non-rotative concentric hollow shaft 17 which forms a rigid horizontal axial support for the roll.

20 25 The cylindrical periphery of the roll is covered with fabric 18. The horizontal non-rotative hollow shaft 17 is rigidly secured in fixed relation to a suitable stationary supporting hub or bearing 19 which is on and preferably formed integrally with the stationary upright upper metallic casing or frame portion 5 and projects outward horizontally from the latter. (See Fig. 4.)

30 35 The non-rotative hollow shaft 17 extends longitudinally through and in concentric supporting engagement with the rotative ironing roll 14; and an axial rod 37 which is fixed to and adapted to form the rotative axle of the ironing roll, is rotatively mounted in concentric relation to and extends lengthwise through the non-rotative hollow shaft 17 from end to end thereof. Said axial rod 37 is connected at its outer end in fixed relation to the ironing roll 14 by suitable connecting means.

40 45 50 55 For example, a metallic securing dog 17', having an axial opening through which the rod 37 extends, is fixed to said rod by means of a securing screw 18' and is fixed to the roll head 16 by a removable pin 19'. The dog 17' has a concentric hollow hub 20' which projects into and is journaled in a bronze end bearing 21' in the stationary hollow shaft. The hub 20' is fixed to and adapted to rotate with the axial rod or rotative axle 37 and the ironing roll is fixed to said axle or axial rod.

60 65 65 The ironing roll and its rotative axle 37 are adapted to be connected with and disconnected from suitable driving mechanism which may be of any ordinary, well known or suitable form. For example, an upright main driving shaft 20 is provided and operatively connected with an electric motor 21 by a suitable train of gears—not shown—enclosed within a gear case 22.

The motor is mounted on a suitable supporting frame 23 within the enclosed chamber formed by the lower casing 4 and hollow base 2, with the motor shaft upright, and may be of any ordinary, and well known or 70 suitable form.

The upright shaft 20 is formed in two sections which are connected by a slotted sleeve 24 fixed to one of said sections and forming a socket into which the adjacent end of the other section extends; and a transverse pin 25 fixed to the other shaft section has its opposite projecting ends seated in the slots 26 in said sleeve.

75 The upper end section of the upright driving shaft 20 is journaled in an upper bearing 27 and a lower bearing 28. Said lower bearing is provided with a packing ring 29 which surrounds the shaft and is held in place by a packing gland 30; and an oil chamber 31 80 is provided, for oiling the packed bearing.

85 90 95 A worm 32 is fixed to the upper end of the upright shaft between the bearings 27 and 28 and is in threaded engagement with a worm wheel 33 which is loosely mounted on the end of the axial rod or shaft 37 which forms the rotative axle of the ironing roll. The worm wheel 33 is adapted to be operatively connected with and disconnected from said axial shaft or rotative shaft 37 and ironing roll by 95 suitable clutch mechanism for operatively connecting the ironing roll and its rotative axle with the driving mechanism when the roll is to be rotated, and for disconnecting the same when the roll is to be allowed to stop or 100 remain stationary during the continued operation of the driving mechanism. The worm wheel 33 is provided with an elongated hub 34 which extends into the adjacent open end of the non-rotative hollow shaft 17 which is provided with a bronze journal bearing 35 in which the said hub and worm wheel are rotatively supported. The bronze bearing is seated in an annular recess 36 in the end of the stationary hollow shaft.

105 110 115 The central horizontal axial rod or rotative axle 37 which is fixed to the ironing roll 14 extends lengthwise through said non-rotative roll-supporting hollow shaft 17 from end to end thereof and projects endwise beyond the inner end of the said hollow shaft and through an axial opening 38 in said hub 34 and worm wheel 33.

120 125 130 Suitable clutch mechanism comprising an ordinary and well-known form of shouldered clutch having the usual inner and outer shouldered clutch members which are in common use in the art to which this invention relates is provided for operatively connecting the rotative axial shaft or axle 37 and ironing roll 14 with the worm wheel 33 and driving mechanism and for disconnecting the same, as follows:

130 An outer clutch member 39, having inner teeth or clutch shoulders 40 in an axial open-

ing 41 in said clutch member, is fixed to the worm wheel 33; and an inner clutch member 42 is slidably mounted on the inner projecting end of said axle and provided with outer 5 clutch teeth or shoulders 43 on the main body portion 44 of said inner clutch member and adapted to be moved into and out of clutching engagement with the adjacent clutch teeth or shoulders 40 on the outer clutch member 39 10 by the movement of said inner clutch member endwise on said axle.

The endwise movable inner clutch member 42 is provided with a central axial opening 45 through and in slidable, but relatively non- 15 rotative engagement with which the rotative axial shaft or axle 37 extends. The clutch-encircled end portion of the rotative axial shaft or axle 37 is provided with a pair of peripheral keys 44 seated therein on opposite 20 site sides of the axial center of said axle and adapted to extend into and in longitudinally slidable engagement with opposite elongated inner peripheral slots 46 in the inner wall of said inner clutch member. The inner 25 clutch member 42 is thus freely movable longitudinally of the rotative axle 37 and is adapted to rotate with said axle and the ironing roll. A spiral clutch-actuating compression spring 47 is interposed between a peripherally flanged end collar 48 on the endwise movable clutch member 42 and a peripherally projecting annular end washer 49 on the end of the axial rod 37, and is adapted 30 to shift said clutch member when the spring 35 is extended, thus acting to operatively connect the axle and ironing roller with the driving mechanism. A clutch-actuating yoke 50, having forked arms 51 which straddle the movable inner clutch member 42 and engage 40 the peripherally projecting cup-shaped flanged collar 48 on said inner clutch member, is pivotally mounted on a supporting bracket 52 by means of a supporting pivot 53 and adapted to shift said clutch member 42 45 against the tension and yielding pressure of the spring 47 to clutch-releasing position out of engagement with the outer clutch member 39, for disconnecting the ironing roll 14 and axle 17 from the driving mechanism.

50 The clutch-actuating yoke 50 is provided with a lever arm 54 fixed thereto for rocking said yoke on its pivotal axis to operate the movable clutch member in one direction to clutch-engaging position and in an opposite 55 direction to release the clutch; and a clutch-actuating connecting link 55 is operatively connected with said lever arm by means of a flanged sleeve 56 in the lever arm and forked arms 57 on the upper adjacent end of said link and in engagement with said sleeve. The 60 clutch-operating link 55 is operatively connected with and adapted to be automatically actuated by and concurrently with the mechanism for operating the ironing shoe, as will 65 more fully appear.

An ironing shoe 58 which may be of any ordinary and well known or desired form, is mounted adjacent to and in normally parallel relation to the ironing roll and adapted to be moved toward and from the roll which is 70 located in front of the shoe.

The ironing shoe shown in the accompanying drawings comprises a concave metallic front plate 59 having a polished concave front ironing surface which faces toward and 75 is adapted to be moved into and out of operative engagement with the similarly curved periphery of the ironing roll or any articles or material which may be inserted between the ironing shoe and roll to be operated upon thereby; and a backing plate 60 is fixed to and adapted to support the front concave ironing plate and provided with a flanged margin which is adapted to be secured in snugly fitting engagement with the front 80 plate. A closed heating chamber is thus formed between the front and back plates of the ironing shoe; and suitable heating means of any ordinary, well known or desired form is enclosed within the chamber 85 thus formed in the shoe. For example, the usual electrical heating element 61 is enclosed within the heating chamber of the ironing shoe and connected with a source of electric supply, for heating the ironing shoe. 90

The ironing shoe 58 is supported upon the rocking shaft and lever mechanism comprising a horizontal rock shaft 62 which is rockingly supported in stationary bearings 63 in the ends of a stationary non-rotative hollow 95 rigid supporting tube 64, one end of which is firmly and rigidly seated in a horizontal opening or socket 65 in a rigid outer bearing member 66 on or formed integrally with the upper frame or housing 5, already described. 100 The opposite outer end of the rock shaft projects outward endwise beyond the projecting end of the stationary tubular supporting member 64 and is provided with a lever arm 67 fixed to said projecting end of the rock 105 shaft and extending upward therefrom directly back of the longitudinal center of the ironing shoe. The upper end of the lever arm 67 is provided with integral forked arms 68 which are spaced apart and perforated; 110 and a hinge member or bracket 67' is fixed to the back longitudinal central portion of the back plate 60 of the ironing shoe and provided with a pair of rearwardly extending hinge or bracket arms 69, the rear outer ends 115 of which are perforated and spaced apart and extend between the forked arms 68 on the rocking lever arm, 67. A horizontal headed hinge pin 70 extends through the aligned openings in the perforated arms 68 and 69 and is held in place by a nut 71 on the screw-threaded end of said hinge pin. A spiral spring 72 encircles the said hinge pin and comprises a pair of integral spring arms 73 and 74 on the opposite extremities of the 120 spiral spring which are adapted to extend

downward between the lever arm 67 and the ironing shoe and tend to press the lower margin of the ironing shoe toward the back peripheral surface of the ironing roll and 5 yieldingly hold the shoe at the proper elevation and angle of inclination and prevent sagging of the shoe while permitting the desired flexibility of movement of the shoe to compensate for any irregularities in thickness 10 in the articles and material to be operated upon between the ironing roll and shoe.

A shoe-actuating lever arm 75 is rigidly secured in fixed relation to the inner end of the rock shaft 62—which extends through 15 and in tightly fitting engagement with the perforated end 76 of said lever—by means of a transverse securing pin 77 mounted in transverse openings in the rock shaft and lever.

20 The lever arms 67 and 75, thus connected with the opposite ends of the rock sheet 62, form an upper pair of rigidly connected rocking lever arms which with the rock shaft are operatively connected with and adapted 25 to support and rock with the ironing shoe.

The lever arm 75, by preference, is formed of heavy stamped metal bent into the form of a straight channel bar having a horizontal top web and upright parallel depending side 30 flanges, and a strong perforated head or end through which the end of the rock shaft extends, as already described.

An intermediate individual actuating lever 35 78 is provided which is formed, by preference, of heavy metal and comprises a bottom web 79 which extends beneath and in movable relation to the lever arm 75, and integral parallel upright marginal side flanges 80 which extend upward on the outside of the 40 opposite side margins of said lever arm 75 so as to enclose the latter between said upright side flanges. Said lever arm 78 has an integral perforated end head portion 81 through which the adjacent inner end of the 45 rock shaft 62 extends in supporting engagement with said lever. It should be noted that the lever arm 78 and the rigidly connected pair of lever arms and rock shaft 62 are all adapted to rock upon the same axis.

50 Formed by the horizontal rock shaft, and that the lever arm 78 is adapted to rock relatively to said rigidly connected pair of lever arms 75 and 67, ironing shoe 58 and rock shaft 62 and upon the same axis. The lever 55 arm 78 is of greater length than the lever arm 75 and extends endwise beyond the same and is adapted to be operatively connected with a second lower pair of rigidly connected manually-operable rocking lever arms for 60 actuating the upper set of levers to effect the movement of the ironing shoe toward and from the ironing roll, as will more fully appear.

Resilient connecting means is provided for 65 forming a yielding connection between the

intermediate individual rocking actuating lever 78 and the adjacent lever arm 75 on the rock shaft, and comprises a headed spring-pressed bolt 82 the lower headed end 83 of which extends through and is seated in an opening in the bottom web 79 of the lever 75 with the head in engagement with the bottom face of said lever. Said bolt extends upward through an opening in the relatively short lever arm 75 and projects upward beyond the latter; and a helical compression spring 84, which encircles the bolt, is interposed between an annular end washer 85 on the upper end of the bolt and a washer 86 mounted on the bolt and held in yielding engagement with the top face of the lever arm 75 by said spring. The washer 85 is held in operative position and adapted to be adjusted upward or downward on the bolt by a nut 87 for regulating and changing the tension of the spring as desired. The relatively long individual rocking lever 78 is thus adapted to actuate the lever arm 75 and thereby rock the rock shaft and ironing shoe toward and from the ironing roll; and the spring and rocking lever mechanism constructed as described is adapted to hold the ironing shoe in yielding operative position relatively to the ironing roll. (See Figs. 2 and 3.)

A return spring 88 which has its bottom end in abutting engagement with a supporting bracket or frame arm 89 and its upper end in engagement with the bottom face of the relatively long individual rocking lever 78 and held in place by the bolt head 83 which is encircled by the spring, tends to press said lever 78 upward when the force employed for moving the ironing shoe toward the ironing roll and for holding the shoe against the ironing roll or the material operated upon is removed. (See Figs. 2 and 3.)

Mounted in the hollow pedestal or frame 4 below the upper set of rocking levers above described is a second pair or set of manually-operable actuating levers, for actuating the upper set of levers and the ironing shoe, constructed and adapted to operate as follows:

Rockingly mounted in suitable bearings in a rigid stationary supporting bracket or frame member 90 on the machine frame is a horizontal rocking stub shaft 91, one end of which projects outward through the housing or frame, as shown in Fig. 4. To the outer projecting end of said shaft is fixed a removable actuating lever 92 which is, by preference, in the form of a hand lever intended and adapted to be manually operated, but which is capable of being operated either by pedal and foot power or by the hand of the operator, or by power-driven actuating means. Fixed to the opposite inner end of the rock shaft 91 is a lever 93 which, by preference, extends downward from the shaft to which it

is fixed and at an angle relatively to the hand lever 92 which is provided with a handle 94 on its outer end in position to be conveniently operated. The lower or outer swinging end 5 of the lever 93 is operatively connected with the outer swinging end of the intermediate actuating lever 78 above described, by suitable flexible connecting means comprising, by preference, an upright connecting rod 95 to the upper end of which is fixed a circular disc or head 96 having preferably on both sides thereof flat side surfaces encircled by integral annular peripheral flanges 97, which project somewhat beyond 10 the flat side surfaces and form shallow flange-encircled recesses, in each of which is mounted a friction disc or washer 98 formed of commercial fiber or other suitable form of somewhat compressible or elastic material adapted 15 to afford the required friction for retarding the upward releasing movements of the lever mechanism. These friction discs are interposed between the recessed disc or head 96 and the adjacent flat perforated ends of the 20 upright side flanges 80 on the outer swinging end of the lever 79; and a transverse screw-threaded pin or bolt 99 extends through aligned axial openings in the head 96, friction discs or washers 98 and flanged end portions 25 of the lever 79, with its threaded end in threaded engagement with one of the flanges 80, and its head 100 in engagement with the other flange 80. The pin or bolt 99 serves to pivotally connect the connecting 30 rod 95 with said lever 78 and to clamp the friction-producing discs or washers 98 between the opposed friction surfaces of the head 96 and said perforated ends of the side flanges 80 on said lever 78, and the friction 35 can be increased or decreased and controlled by turning the bolt in the required direction for its proper adjustment. An adjustable locking plate 101 having an angular opening therethrough adapted to fit around and in 40 fixed relation to the angular bolt head 100, and having a segmental slot 102 through which extends a headed securing screw 103, the inner threaded end of which is mounted in threaded engagement with a suitable 45 threaded opening in the adjacent upright side flange 80 of the lever 78, affords a very simple and efficient means for securing and locking the headed clamping bolt 99 against rotation in any adjusted position in which it is set. 50 The lower end of the connecting rod 95 is connected with the lower swinging end of the lever arm 93 by means of a connecting link 104, the lower end of which is connected with said lever arm by a transverse connecting 55 pivot pin 105, and the upper end of which is connected with the connecting rod by a transverse connecting pivot pin 106 which extends through the perforated ends of the integral side flanges 107 on said link and through a 60 suitable transverse opening in the bottom end 65 head 108 fixed to the bottom end of said connecting rod and adapted to extend between said perforated side flanges 107. (See Figs. 2 and 4.)

A locking link 109 is pivotally connected 70 at its lower end with the perforated bottom headed end 108 of the connecting rod 95 and the upper end of the link 104 by the transverse pivot pin 106, already described, as best shown in Fig. 4. The locking link 109 is supported at its upper end by a supporting arm 110 which, by preference, is stationary and connected with the bracket 90 in which the rock shaft 91 is rockingly supported. The front end of said supporting arm 110 is provided with suitable perforated forked arm portions 111 between which the upper end of the link extends; and a transverse connecting pivot pin 112 extends through the 75 perforations in said forked arms and through a suitable perforation in the upper end of said locking link. A stopping and releasing or tripping arm 113 is, by preference, fixed to the lever arm 93 in position to engage and stop the lower headed end of the connecting rod 95, or a stop connected with said rod, when the bottom end of said lever arm and the connecting pivot pin 106 in the bottom end of said rod are moved downward and 80 backward past the approximately vertical plane in which the axial centers of the pivot pin 112 and upper connecting pin or bolt 100 in the connected ends of the connecting rod 95 and rocking lever 78 are located. As soon as the axial center of the pivot 106 85 passes downward and rearward past the dead center represented by an imaginary line through the axes of the pin 112 and the upper pin or bolt 100, concurrently with the downward movement of the hand lever 92 from the 90 position in which it is shown in Fig. 3, to the position in which it is shown in Fig. 2, in the operation of moving the ironing shoe forward into operative engagement with the ironing roll or the material to be operated 95 on, the locking link 109 acts to lock the parts in said position. The first part of the upward movement of the hand lever 92 and the lever arm 93 upon the axis formed by the 100 lower rock shaft 91 with which said levers 105 are rigidly connected, causes the stop arm 113 and the lever 93 to engage and release or trip the connected bottom ends of the connecting rod and link 109 and upper end of the link 110 by forcing the connecting pin 106 and the parts connected thereby forward and past 110 said dead center and out of locking position and permitting the connected levers and the parts connected therewith, including the ironing shoe and lever arms 78, 75 and 67, to 115 be returned by the spring 88 to the position in which they are shown in Fig. 3.

A stop 114 on the lever 93 is adapted to engage a stationary stop 115 formed by the lower edge of the arm 110 so as to limit the 120 125 130

forward movement of the lever 93 and the connecting rod and link mechanism as shown in Fig. 3.

The clutch-actuating link 55, above described, is connected at its lower end with the intermediate rocking lever 78 loosely supported on the rock shaft 62 by means of a transverse pivot pin 116 which is anchored in and projects transversely beyond the side 10 of the said lever and extends through a suitable opening in the lower end of said link. Means is thus afforded for automatically actuating the clutch for connecting the ironing roll with the driving mechanism by and 15 concurrently with the operation of the ironing shoe forward into operative engagement with the ironing shoe or the material to be operated upon, and for automatically actuating said clutch for releasing the connection 20 between the ironing roll and the driving mechanism to stop the roll and permit it to remain stationary concurrently with the releasing of the ironing shoe and its movement away from the ironing roll.

Means is provided for causing the ironing roll to stop or remain stationary during the continued and uninterrupted operation of the driving mechanism, and independently of the position of the ironing shoe and its actuating 25 mechanism, and comprises, by preference, a small clutch-releasing rock shaft 116 which is rockingly supported in a suitable bearing 117 in the front upper portion of the machine frame or housing in position to extend under 30 and closely adjacent to the lever arm 54 on the clutch-actuating yoke 50. Fixed to said rocking shaft 116 directly beneath the said lever arm 54 is an eccentric 118 which is adapted to engage and raise the said lever 35 and operate and hold the clutch-actuating yoke in clutch-releasing position when the eccentric is rotated to its raised position by the partial rotation of said clutch-releasing rock shaft. To lower and release the lever 40 arm 54 and permit the clutch to be engaged it is only necessary to lower the eccentric out of engagement with said clutch-actuating lever and yoke by the partial rotation of the rock shaft 116 on which the eccentric is fixed. 45

A small clutch-releasing hand lever 119 is fixed to the outer end of the clutch-releasing rock shaft 116 for operating it for releasing or permitting the engagement of the clutch. Stationary stops 120 and 121 on the outside 50 of the housing are adapted to engage and limit the movements of the clutch-releasing lever 119 in either direction.

The usual electric switch mechanism 123 is enclosed within an inner housing or switch 60 box 124 within the hollow pedestal or frame housing.

In operation, the driving mechanism is started by operating the electric switch 123 to close the electric circuit with which the 65 motor is connected. The hand lever 94 is

then operated by pressing it downward to the position shown in Fig. 3 which causes the ironing shoe to be moved forward into operative engagement with the ironing roll and the material to be operated upon, and causes the ironing roll to be releasably connected with the driving mechanism by the clutch mechanism concurrently with the forward movement of the ironing shoe by the shoe-actuating lever mechanism and the clutch-actuating mechanism connected therewith. To disconnect the ironing roll from the driving mechanism it is only necessary to raise the hand lever 94 sufficiently to release and permit the return of the ironing shoe and shoe-actuating mechanism and connected clutch mechanism to initial position.

The upward movement of the released hand lever is retarded by the friction producing means interposed between the upper 85 end of the connecting rod 95 and the shoe-actuating lever arm with which said rod is connected thereby preventing unnecessary shocks and strains to the mechanism and danger of injury to the operator or others. The 90 rotation of the ironing roll may be stopped without stopping the operation of the driving mechanism by operating the small hand lever 119 and the eccentric operated thereby which is raised to hold the clutch disengaged 95 and lowered to permit the clutch to engage and operatively connect the driving mechanism with the ironing roll.

We claim:

1. In an ironing machine, a rotative ironing roll, an ironing shoe located adjacent to and movable toward and from said ironing roll, a pair of connected lever arms supported and adapted to rock upon a common axis, means for connecting one of said pair of connected lever arms with the ironing shoe, an intermediate individual actuating lever connected with the other one of said pair of connected lever arms and rockingly mounted in movable relation to and adapted to rock upon the same axis with said pair of connected lever arms, a connecting rod pivotally connected with said intermediate individual rocking lever, a second pair of connected rocking lever arms supported independently of said first-mentioned pair of connected lever arms, and means associated with and adapted to be operated by said last-mentioned pair of connected lever arms and connected with and adapted to operate said connecting rod, for actuating and locking and releasing the shoe-actuating lever mechanism and ironing shoe.

2. In an ironing machine, a rotative ironing roll, an ironing shoe located adjacent to and movable toward and from said ironing roll, a set of connected shoe-actuating lever arms comprising a pair of rigidly connected rocking lever arms and an individual relatively movable rocking lever all supported 125

ing means to permit the movement of the ironing shoe away from the ironing roll.

7. In an ironing machine, the combination of an ironing roll, an ironing shoe located adjacent to and movable toward and from said ironing roll, an upper pair of connected rocking lever arms one of which is connected with and adapted to support the ironing shoe, an intermediate individual actuating rocking lever adapted to rock upon the same axis with and relatively to an adjacent one of said pair of connected rocking levers, resilient connecting means connected with and forming a yielding connection between said individual actuating rocking lever and said adjacent one of said pair of connected rocking levers, a second pair of manually operable connected lever arms, connecting means connected with and forming a flexible connection between said second pair of manually operable connected rocking lever arms and said intermediate individual actuating rocking lever, and locking means comprising a locking member mounted on a stationary support and pivotally connected with said flexible connecting means and adapted to be operated by said manually operable lever mechanism and said flexible connecting means for locking and releasing the shoe-operating lever mechanism and ironing shoe.

8. In an ironing machine, the combination of a rotative ironing roll, an ironing shoe located adjacent to and movable toward and from said ironing roll, an upper pair of connected rocking lever arms one of which is connected with and adapted to rockingly support the ironing shoe, an individual actuating rocking lever adapted to rock upon the same axis with and relatively to an adjacent one of said pair of connected rocking lever arms, resilient connecting means connected with and forming a yielding connection between said last-mentioned rocking lever arm and said individual actuating rocking lever, a second pair of manually operable connected lever arms rockingly supported independently said first-mentioned pair of connected lever arms, connecting rod and link mechanism connected with and forming a flexible connection between said pair of manually operable connected lever arms and said individual actuating rocking lever, a pivotally supported locking link member connected with a stationary support and with said connecting rod and link mechanism and adapted to be operated by said manually operable lever mechanism and said connecting rod and link mechanism for locking said shoe-operating lever mechanism and ironing shoe in locked operative position, and means connected with and adapted to be actuated by said manually operable lever mechanism for releasing said locking means and ironing shoe.

9. In an ironing machine, the combination of a rotative ironing roll, an ironing shoe located adjacent to and movable toward and from said ironing roll, an upper set of connected shoe-actuating rocking levers rockingly mounted upon a common horizontal axis in supporting engagement with the ironing shoe for supporting and rocking the same toward and from the ironing roll, manually operable rocking lever mechanism comprising a hand lever and a rigid rocking lever arm connected with and adapted to be actuated by said hand lever, a connecting rod pivotally connected with one of the lever arms of said first-mentioned set of connected levers, locking link mechanism pivotally mounted upon a stationary support and pivotally connected with the lower end of said connecting rod, and connecting means connected with and adapted to form a pivotal connection between said locking link mechanism and said connecting rod and manually operable rocking mechanism, said last-mentioned pivotal connection and said locking link mechanism being adapted to be shifted by the manually operable lever mechanism into and out of locking position relatively to the pivotal connection between the connecting rod and said upper set of connected rocking levers and the pivotal connection between said locking link mechanism and its stationary support.

10. In an ironing machine, the combination of a rotative ironing roll, driving mechanism for rotating said roll, an ironing shoe located adjacent to and movable toward and from said ironing roll, an upper pair of connecting rocking lever arms, one of said lever arms being connected with and adapted to support the ironing shoe, an intermediate individual rocking lever adapted to rock upon the same axis with said pair of connected rocking lever arms, resilient connecting means forming a yielding connection between said last-mentioned individual rocking lever and said first-mentioned pair of connected rocking lever arms, a second pair of manually operable connected rocking lever arms, connecting rod and link mechanism forming a flexible connection between said last-mentioned manually operable connected lever arms and said intermediate individual rocking lever, a pivoted locking member connected with said connecting rod and link mechanism and adapted to be operated by said manually operable lever mechanism and said connecting link mechanism for locking said connecting rod and ironing shoe in locked position, means on and adapted to be operated by said manually operable rocking lever mechanism for releasing said locking means to release the connecting rod and ironing shoe and permit the movement of the shoe away from the ironing roll, clutch mechanism connected with said driving mechanism and

adapted to be connected with and disconnected from the ironing roll for connecting said roll with said driving mechanism and disconnecting the same, and means on and 5 adapted to be actuated by said intermediate individual rocking lever and operatively connected with said clutch mechanism, for operating the same.

Signed at Chicago, in the county of Cook
10 and State of Illinois, this 3rd day of October,
1929.

EDWARD C. PETER.
HENRY C. SCHUKNECHT.
RAYMOND D. SCHNOOR.
